J. HEAP.

VEGETABLE DISH.

No. 15,145.

Patented July 15, 1884.

Fig. 1.

Fig. 2

UNITED STATES PATENT OFFICE.

JOSEPH HEAP, OF BURSLEM, COUNTY OF STAFFORD, ENGLAND, ASSIGNOR
TO JOHN HALL, OF BOSTON, MASSACHUSETTS.

DESIGN FOR A VEGETABLE-DISH.

SPECIFICATION forming part of Design No. 15,145, dated July 15, 1884.

Application filed April 25, 1884. Term of patent 3½ years. Patented in England March 5, 1884, No. 2,965.

To all whom it may concern:

Be it known that I, JOSEPH HEAP, a subject of the Queen of Great Britain, residing at Burslem, in the county of Stafford, England, have invented and produced a new and original Design for Vegetable-Dishes and other Table-Ware, of which the following is a specification, reference being had to the accompanying photographs, forming part thereof, in which—

Figure 1 is a view of a vegetable-dish and its cover made in accordance with my new design. Fig. 2 is a view of the dish, the cover being removed.

15 This invention relates to a new configuration for a vegetable-dish or other china household article, such as a tureen, sauce-boat, pitcher, tea-pot, or sugar-dish.

The dish A is made of rectangular form, the 20 two opposite sides, *b b' c c'*, being parallel and joined by slightly-rounded corners. Each side is composed of an outwardly and downwardly inclined portion, *d*, united at *e* to a slightly-convex lower portion, *f*, extending downward

25 and inward to the bottom, which is provided with feet *g*. At the upper edge of the dish is formed a small bead, *h*, and at the center of each end is a handle, *i*.

The rectangular cover B is of pyramidal 30 form, having four approximately triangular

convex faces, *k*, forming angles at their points of intersection, the lines of intersection *l* extending diagonally from the corners of the cover to the apex, which is surmounted by a handle, *m*.

35

What I claim as my invention, and desire to secure by Letters Patent, is—

1. The design for a rectangular vegetable-dish, having parallel sides formed of outwardly and downwardly inclined upper portions, *d*, 40 having a bead, *h*, at the upper edge, and handles *i*, and the convex lower portions, *f*, extending downward and inward from the portions *d* to the bottom, and having feet *g*, substantially as herein shown and described. 45

2. The design for the rectangular cover B, having four approximately triangular convex faces, *k*, extending upward from the lower edges, and having a curved pyramidal upper portion terminating in a pointed apex surmounted by a handle, *m*, substantially as herein shown and described. 50

Witness my hand this 2d day of April, A. D. 1884.

JOSEPH HEAP.

In presence of—

F. W. TOURKMAN,
Solicitor, Burslem.
JOHN H. COPESTAKE.
